UNITED STATES PATENT OFFICE.

ORRIN S. STEVENS, OF BELVIDERE, NEW JERSEY.

DESIGN FOR HUB-BANDS FOR VEHICLE-WHEELS.

Specification forming part of Design No. 6,247, dated November 12, 1872.

To all whom it may concern:

Be it known that I, ORRIN S. STEVENS, of Belvidere, in the county of Warren and State of New Jersey, have invented a new and valuable Improvement in Metallic Bands for Hubs; and I do hereby declare that the following is a full, clear, and exact description of the construction and operation of the same, reference being had to the annexed drawing making a part of this specification, and to the letters and figures of reference marked thereon.

Figure 1 of the drawing is a representation of a perspective view of my invention. Fig. 2 is a central section of my invention. Fig. 3 is a detail view of my invention.

My invention has relation to a novel design for the configuration of hub-bands of carriage-wheel hubs having a "stagger" arrangement, and is fully illustrated in the accompanying drawing.

The ring A has its edges scalloped for the purpose of ornamentation. The spoke-mortises B are formed in the raised or thick part

of the ring, and are wedge-shaped and disposed in "stagger" order. These mortises lie nearer the inner than the outer end of the ring. From the ends of said mortises to the edges of the ring the surface of the ring falls in gentle wave-like curves, which terminate at or near the surface of the hub. The ring itself is of a tapering form and may be tightly driven on the hub. The appearance of the ring may be greatly improved by gilding or silver-plating the surface.

What I claim as my invention, and desire to secure by Letters Patent, is—

The design for a hub-ring, having wave-like edges and surfaces, as shown and described.

In testimony that I claim the above I have hereunto subscribed my name in the presence of two witnesses.

ORRIN S. STEVENS.
